UNITED STATES PATENT OFFICE.

JOHN HENRY CARROLL, OF MONTREAL, QUEBEC, CANADA.

NECKTIE.

1,023,196.

Specification of Letters Patent. Patented Apr. 16, 1912.

Application filed August 21, 1911. Serial No. 645,201.

To all whom it may concern:

Be it known that I, JOHN HENRY CARROLL, of the city of Montreal, Province of Quebec, Dominion of Canada, have invented 5 certain new and useful Improvements in Neckties; and I do hereby declare that the following is a full, clear, and exact description of the same.

The object of the present invention is to 10 provide a complete tie comprising two distinct portions connected in such a manner that they can be readily separated and thereby facilitate the withdrawal of the necktie from the collar while the tie is 15 knotted.

For full comprehension however, of my invention reference must be had to the accompanying drawings forming a part of this specification in which similar reference 20 characters indicate the same parts and wherein:

Figure 1 is a top view of my improved necktie; Fig. 2 is an enlarged view illustrating the members of the locking device; Fig. 25 3 is a longitudinal sectional view of the locking means; and Fig. 4 is a view illustrating my improved necktie in use.

Although my improved necktie can be used with any collar it is adapted for use 30 with double fold collars and specially in connection with the so called close fitting collars.

Heretofore difficulty has been encountered when untying the knot of a four-in-hand 35 necktie when worn with a close fitting collar, in that in untying the knot the flaps of the collar are liable to become soiled and crumpled, so to overcome this defect I have provided a necktie which comprises two dis- 40 tinct lengths joined together by a locking device which is capable of withstanding the usual amount of pulling and jerking to which the ordinary necktie is subjected and which can be readily released, when in use, 45 by the wearer thereby permitting the necktie to be withdrawn from the collar without the necessity of first untying the knot.

I prefer to locate the above mentioned locking device at a point along the length of 50 the necktie where it will assume a position between the folds of the collar at the side so as to be out of sight and when released the two lengths of the necktie can be slipped from the collar by pulling from the front.

55 The locking device may be in several different forms but the preferred construction

comprises members *b* and *c* carried by the ends of the separate lengths *d* and *e* of the necktie, one of such members *b*, presenting a single aperture *f* while the other *c*, is formed with two parallel narrow slots *g* placed transversely of the tie and forming between them a bar *h*, both of the said members being composed of light, flexible material such as celluloid and are sewed to their respective portions or otherwise suitably secured thereto. To lock the lengths *d* and *e* together, the members *b* and *c* are placed one above the other, the member *b* uppermost when in the position shown in the drawings, the aperture *f* exposing the bar *h* while a locking pin 60 *i* (of similar material as the members *b* and *c*) is inserted, from the top, through the aperture *f* and one of the slots *g*, beneath the bar *h* and upward through the other slot *g* 65 and aperture *f*, the ends of the pin *i* resting upon the surface of the member *b* and thus locking the members together.

The locking device just described securely holds the lengths *d* and *e* together and 70 forms a complete necktie which may be placed between the folds of the collar and tied as usual.

When it is desired to untie the knot, the stiff flaps of the collar interfere therewith 75 so that when the knot is untied the collar has become soiled and crumpled. To overcome the above mentioned defect I provide means for releasing the locking device, such means being accessible from the front, within 80 easy reach of the wearer of the necktie and comprising a tape or string *j* of silk or any other suitable material, secured at one end to the locking pin from which it extends a short distance along the length of 85 one portion of the necktie, where it is threaded between the plies of the latter to the free end thereof, the end of such string, 90 being exposed and having a knot formed thereon or other suitable means for providing a hold upon the same, so that when it is desired to release the locking means, the string 95 is pulled thereby drawing the pin *i* from its locking position, separating the lengths *d* and *e* and permitting them to be withdrawn 100 without the necessity of untying the knot.

When using my improved necktie, it is preferable to utilize the length containing the string *j* as the portion upon which the knot is formed by this means leaving it, as 105 far as possible, straight so as to prevent folding of such portion and binding of the

string when it is pulled to release the locking device.

The locking device may be used in connection with a stand up, single fold collar in which case the necktie, with the knot still formed and the tie released and removed as just described, may be again applied to the collar by placing the tie in position and locking the lengths together by the pin *i*.

10. What I claim is as follows:

1. The combination with a necktie including two distinct portions, a member attached to one of the said portions, a second member attached to the other of the said portions, and means for securing such members together to form the complete necktie,—of a flexible portion connected to the securing means and through the medium of which portion the latter is displaced from

20 its securing position.

2. The combination with a necktie comprising two distinct plain length portions, of engaging members carried by the ends of

said portions, a locking pin, and a flexible portion distinct from both portions of the 25 necktie, secured to and extending from the locking pin for displacing the latter.

3. A necktie comprising two distinct portions, a member carried by one of the said portions and presenting an aperture, a second member carried by the other portion, a bar presented by the second member and adapted to be placed beneath the said aperture, a locking pin adapted to be threaded between the apertured member and the said 30 bar and a string secured to the locking pin, inserted between the plies of one portion of the necktie and extending therebetween to the free end of such portion.

In testimony whereof, I have signed my 40 name to this specification, in the presence of two subscribing witnesses.

JOHN CARROLL.
